CLAIM

(22) Filed: **Aug. 24, 2007**

The ornamental design for a robotic positioning device for a medical imaging unit, as shown and described.

(30) **Foreign Application Priority Data**

DESCRIPTION

Mar. 1, 2007 (EM) 000690003

FIG. 1 is a front view of the robotic positioning device for a medical imaging unit;

(51) **LOC (9) Cl.** 24-01

FIG. 2 is a rear view thereof;

(52) **U.S. Cl.** D24/158

FIG. 3 is a top view thereof;

(58) **Field of Classification Search** D24/158–161,

FIG. 4 is a bottom view thereof;

D24/183, 186; 378/4, 15, 17, 19, 20, 21–27,

FIG. 5 is a right side view thereof;

378/38–40, 102, 146, 195, 197, 198; 600/409,

FIG. 6 is a left side view thereof; and,

600/410, 425, 476; D15/199

FIG. 7 is a perspective view thereof.

See application file for complete search history.

(56) **References Cited**

The broken lines in the drawings are for illustrating portions of the robotic positioning device that form no part of the claimed design.
